UNITED STATES PATENT OFFICE.

WILLIAM BARBER, OF BROOKLYN, NEW YORK.

SHEET-METAL WHEEL.

Application filed April 15, 1919. Serial No. 290,208.

This invention relates to sheet metal wheels. The object of the invention is to provide a sheet metal wheel which is simple and inexpensive in construction, which is strong, durable, and wherein a desirable degree of resiliency in the wheel structure is secured.

Other objects of the invention will appear more fully hereinafter.

The invention consists substantially in the construction, combination, location, and relative arrangement of parts, all as will be more fully hereinafter set forth as shown in the accompanying drawings, and finally pointed out in the appended claims.

In the drawings,—

Fig. 1 is a view in side elevation of a sheet metal wheel constructed in accordance with the principles of my invention.

Fig. 2 is a transverse central sectional view of the same.

Fig. 3 is a detached detail view in side elevation of the wooden spacing ring or block showing the reinforcing metal ring applied thereto.

Fig. 4 is a transverse central sectional view of the spacer shown in Fig. 3.

Fig. 5 is a view similar to Fig. 2 showing a modified structure embodying the principles of my invention.

Fig. 6 is a broken detail view in perspective showing the double reinforcing ring structure of Fig. 5 applied to the wooden spacer bar.

Fig. 7 is a detached detail view of one form of clamping bolt employed in connection with a wheel of my invention.

Fig. 8 is a view in side elevation of a reinforcing flange ring for the felly structure of wheel shown in Fig. 5.

Fig. 9 is an edge view of the ring shown in Fig. 8.

The same part is designated by the same reference numeral wherever it occurs throughout the several views.

Reference numeral 10 designates the wheel hub. This may be of any desired structure or formation, and while I have shown a hub structure as applied to a floating axle type, I wish it to be understood that my invention is not to be restricted or limited in this respect.

In the particular type shown 12 is the driving member mounted on the shaft 13 and rotating therewith and with the wheel. 14 is the axle cap. In practice the hub 10 and driving member 12 are constructed with annular flanges 15, 16, respectively, which are bolted or otherwise secured together and to the

wheel. Mounted upon the hub sleeve 10 and also suitably bolted or otherwise secured to the wheel and to the hub sleeve and driving member 12 is brake drum 17.

The parts so far described may be of any suitable or well known structure, and in the details thereof form no part of my present invention.

The sheet metal wheel embodying my invention includes the disks 18, 19, suitably stamped out and dished, and each formed with a central flanged opening. For example, the disk 18 is formed with a central flange 20 while the disk 19 is likewise provided with the central flange 21. The flange 20 of disk 18 extends outwardly and fits annularly upon the hub sleeve 10. The flange 21 of disk 19 extends inwardly and fits annularly upon the flange 20. These flanged central portions of the disks are received in the channel formed between the hub sleeve flange 15 and the opposed surface of the brake band drum 17. Disposed between the disks 18, 19, and surrounding the flanges 20, 21, thereof, is a ring shaped wooden block 22 which performs the function of a spacer block for the disks and at the same time affords a desirable degree of resiliency or yielding of the wheel structure in use avoiding that rigidity which an all-metal structure ordinarily presents. The wooden spacer block 22 occupies the space between the opposed surfaces of the disks 18, 19, adjacent to the central portions of said disks and radially from the spacer block the disks are brought into contact and secured together at their peripheral edges.

In order to secure the desired reinforcement for the disk 18 and a keeper to retain the wooden block 22 in place and to prevent the latter from becoming split or injured in use a reinforcing metal ring member 23 is applied to the exterior surface of the wooden ring 22, said reinforcing ring if desired, being formed or stamped with lugs or flanges 24 which are riveted or otherwise secured to the exterior face of disk 18. This reinforcing metal ring 23 not only serves to properly retain the wooden spacer block in place and prevent the same from splitting but also reinforces and stiffens the disk 18, while at the same time permitting a desirable degree of resiliency thereof.

It will be observed that the wheel disk 19 at a point intermediate its central hub opening and its main body portion, is formed with an outwardly curved portion which merges

into the main body portion, thereby forming in effect an ogee curved portion, which serves to materially strengthen and stiffen the disk particularly in the region of its hub where the greatest load strain occurs when the wheel is in use.

In order to still further stiffen the disks 18, 19, I prefer to stamp therein circular grooves 25 in the contacting surfaces thereof, which grooves nest the one into the other. These grooves are formed near the peripheral portions of the disks which lie flatwise against each other.

Any suitable or convenient rim structure or tire retaining device may be employed in connection with a stamped metal wheel embodying my invention. In the arrangement shown in Fig. 2, 26 designates an angle shaped tire retaining rim section, the angle 20 of which fits over the peripheral edges of the sheets or disks 18, 19. A securing bolt 27, see Fig. 7, is passed through the two disks 18, 19, and the angle flange 28 of the rim member 26. A cooperating rim member 29 is also 25 detachably retained in place by the nut 30 on the bolt 27. In this form of my invention the bolt 27 is provided with an elongated head 31 which fits flatwise against the inner face or surface of the disk stamping 18 and 30 is riveted or otherwise permanently secured thereto. By simply removing the nuts 30 from the bolts 27 the tire retaining rim sections 29, 26, may be removed, or the members or lugs 29 may be removed to permit the removal of the tire.

In the arrangement shown in Figs. 5 and 6 a slightly modified arrangement is shown wherein two stiffening rings or bands 32, 33, having if desired, the lugs 34 stamped therein, are employed in place of the stiffening and retaining band or ring 23 above described with reference to the structure shown in Figs. 2, 3 and 4. The retaining and stiffening band or ring 33 has its lugs 34 riveted or otherwise secured to the disk 18, while the band or retaining ring 32 has its lugs 34 riveted or otherwise secured to the disk 19, the two rings or bands 32, 33 being nested or telescoped the one upon the other.

I have also shown a modified arrangement of tire retaining devices in the structure shown in Fig. 5. In this instance the peripheral edge portions of the disks 18, 19 themselves constitute one member of the tire retaining structure, said edges being bent laterally or into angular relation with respect to the body portions of the disks 18, 19, and the extreme peripheral edge 35 of disk 19 being bent or folded over the extreme edge 36 of the disk 18, the two edges being deflected upwardly to form a bearing for the tire rim 37 in cooperation with retaining lugs 38. In order to secure greater strength and sturdiness of the tire retaining structure an angle ring member 39 is applied at the angle

formed by bending the peripheral edge portions of the disk into shape to form a tire retaining member. The stiffening flange ring 39, the radial portions of the disks 18, 19 which lie flatwise against each other, and the 70 co-operating retaining lugs 38 are secured together by means of bolts 40, to the ends of which nuts 41 are applied. These bolts may be headed and welded into seats formed to receive the heads in the stiffening ring 39. 75

In the construction shown in Fig. 5, the disks 18, 19, are formed of suitable metal stampings, said disks being flanged at their central openings, said flanges being bent or deflected laterally towards each other to form a central cylindrical portion 50 which constitutes a hub portion which fits on the wheel hub 10. The wooden spacer block 22 in this instance fits the channel formed by bending the disks 18, 19 radially from the hub flange 85 portion 50.

It will be observed that not only does the wooden spacing block or ring serve the function of a spacer for the hub portions of disks 18, 19, but it also serves to deaden the sound 90 and to absorb and take up to a desirable degree the shock of impact over rough roads, thereby securing a desirable degree of resiliency in the wheel.

It will also be observed, see particularly Fig. 5, that the portions of the disks which are brought flatwise together in the region of their peripheral edges, are offset laterally, in this case towards the left, from the central transverse vertical plane through the hub. With this arrangement it will be observed that the flatwise contacting radial portions of the disks are to one side of the central line of the tire when applied. The purpose of this arrangement and construction is to 100 avoid rigidity resulting from a strictly radial relation of the disks, and to secure a desirable degree of resiliency in the wheel structure, permitting it to absorb shock, jar and vibrations when the wheel is in use. 105

From the foregoing description it will be seen that I provide an exceedingly simple, rugged, durable and inexpensive structure of stamped wheels, which, while strengthened by the reinforcing rings or bands described, 110 still afford a desirable degree of yield to absorb the shocks and vibrations due to the operation of vehicles equipped with such wheels over rough places in the roadway. The resiliency in the wheel is contributed to not only by the use of the wooden spacing block 22 but also by the retaining and stiffening rings or bands 23, 32, 33, and by the crimped channels 25, the latter not only permitting a 115 desirable degree of resiliency to absorb shocks, but also securing strength to resist the weight strains imposed thereon.

Having now set forth the objects and nature of my invention and constructions embodying the principles thereof, what I claim 120

as new and useful and of my own invention and desire to secure by Letters Patent is,—

1. In a sheet metal wheel structure, a hub, stamped metal wheel members having inner flanged portions respectively meeting at the center to be received and supported upon the hub, said members also having portions disposed to contact flatwise against each other, and means to space said members apart at their hub portions, and means to secure said members upon the hub. 40
2. In a sheet metal wheel structure, a hub, stamped metal disk members having inner flanged portions respectively extending in opposite directions to be received and supported upon the hub, said disk members also having portions disposed to contact flatwise against each other, a spacing member interposed between said disks at their hub portions and secured over said inner flanged portions, and means securing said disk members and spacing member together on said hub. 45
3. In a sheet metal wheel structure, a hub, stamped metal disks supported thereby, a wooden spacing ring interposed between said disks at the hub portions thereof, and a retaining and stiffening ring member applied around said wooden spacer, the disks being brought into flatwise contact and secured together at their peripheral edges. 50
4. In a sheet metal wheel structure, a hub, stamped metal disks supported thereby, a wooden spacing ring interposed between said disks at the hub portions thereof, and a retaining and stiffening ring member applied around said wooden spacer, said retaining ring being secured to one of said disks, the disks being brought into flatwise contact and secured together at their peripheral edges. 55
5. In a sheet metal wheel structure, a hub, stamped metal disks supported thereby, a wooden spacing ring interposed between said disks at the hub portions thereof, and a pair of retaining and stiffening rings applied around said wooden spacer and telescoped the one into the other, the disks being brought into flatwise contact and secured together at their peripheral edges. 60
6. In a sheet metal wheel structure, a hub, stamped metal disks supported thereby, a wooden spacing ring interposed between said disks at the hub portions thereof, and a pair of retaining and stiffening rings applied around said wooden spacer and telescoped the one into the other, said retaining rings being respectively secured to said disks. 65
7. In a metal wheel, a hub sleeve provided with a securing flange at one end thereof, a pair of sheet metal disks provided with bores at the center thereof, drawn parts of said disks extending inwardly towards each other and telescoping over said hub sleeve, a spacer interposed between said disks and adapted to engage the drawn portions to cause a tight engagement of the latter with the hub sleeve, and means for uniting said hub sleeve, disks and spacer to each other. 70
8. In a metal wheel structure, the combination of a hub having a flange extension, metal disks radially disposed on said hub, said disks having inwardly extending hub parts, a spacer block on said hub bearings, and means for uniting said spacer block hub flange and metal disks to form the wheel. 75

In testimony whereof I have hereunto set my hand on this 14th day of April, A. D. 1919.

WILLIAM BARBER.
